UNITED STATES PATENT OFFICE.

LILLIAN STRASBURGER, OF NEW YORK, N. Y.

DESIGN FOR A LAMP-SHADE OR SIMILAR ARTICLE.

SPECIFICATION forming part of Design No. 34,249, dated March 19, 1901.

Application filed February 18, 1901. Serial No. 47,882. Term of patent 3½ years.

To all whom it may concern:

Be it known that I, LILLIAN STRASBURGER, a citizen of the United States, residing at No. 907 Broadway, New York city, in the county of New York and State of New York, have invented and produced a new and original Design for Lamp-Shades; and I do hereby declare the following to be a full, clear, and exact description of the same, reference being had to the accompanying drawings, forming a part thereof.

My invention relates to a design for a shade for lamps, candles, or the like; and it consists of the configuration shown in the accompanying drawings, forming a part of this specification, and in which—

Figure 1 is a side elevation of a lamp or candle shade, showing my new design; and Fig. 2 is a plan view of the same.

The characteristic or leading feature of my design is its rosebud aspect, with the corolla

of the polypetalous type, and comprising a cluster of petals A, extending upwardly and forming the main or globe portion of the shade, and a series of similar petals B, arranged in circular form about the base of the cluster and pendent therefrom. Alternating with the pendent petals B is a series of serrated lance-like sepals C, which, in combination with said petals, form a lower or hood portion of the shade.

What I claim as new is—

The design for a lamp-shade, or similar article, substantially as herein shown and described.

In testimony whereof I affix my signature in presence of two witnesses.

LILLIAN STRASBURGER.
